A. D. CRAWFIS,
RESHIPMENT CONTAINER.
APPLICATION FILED JUNE 16, 1921.

Patented Oct 3, 1922.

FIG. 1.

FIG. 2.

INVENTOR
Amos D. Crawfis,
By (or) (or) (or) (or)
Atty.

UNITED STATES PATENT OFFICE.

AMOS D. CRAWFIS, OF TOLEDO, OHIO.

RESHIPMENT CONTAINER.

Application filed June 16, 1921. Serial No. 477,871.

To all whom it may concern:

Be it known that I, AMOS D. CRAWFIS, a citizen of the United States, and a resident of Toledo, in the county of Lucas and State 5 of Ohio, have made an Invention Appertaining to a Reshipment Container; and I do hereby declare the following to be a full, clear, and exact description of the invention, such as will enable others skilled in the 10 art to which it appertains to make and use the same, reference being had to the accompanying drawings, and to the characters of reference marked thereon, which form a part of this specification.

15 This invention relates to containers for use in the shipment of parcels and particularly to containers intended for repeated use in shipping merchandise or other matter.

The primary object of the invention is to 20 provide a shipping container which is strong and durable in its construction and may be used for repeated shipments, such, for instance, as sending laundry back and forth between a college student and his home, 25 and which has provision for the affixing of stamps, insurance and other postal markings in such manner as to be prominently displayed and to enable them to be easily and quickly removed for the affixing of new 30 stamps and markings thereby preventing defacing the container, as is customarily the case, by repeatedly affixing stamps and markings of a permanent nature thereto.

Further objects and advantages of the invention will be apparent from the following 35 detailed description.

The invention is described in the following specification, and while in its broader aspect it is capable of embodiment in numerous forms, a preferred embodiment thereof 40 is illustrated in the accompanying drawings, in which,

Fig. 1 is a top plan view of a shipping container embodying the invention, and Fig. 45 2 is an inner side view of the cover thereof with parts broken away.

Referring to the drawings, 1 designates the cover of a container of the telescoping type, although it may be of other form, such 50 cover being made of a stiff durable material, such, for instance, as pressed fiber board which is commonly employed in containers of this class.

In carrying out my invention I provide 55 the top portion of the cover with three win-

dows or openings 2, 3 and 4, the opening 2 having a strip or ribbon 5 of paper or other suitable material movable across the same below the surface of the cover for receiving postage stamps and other postal markings, 60 such, for instance, as insurance designation, parcel post stampings, etc., which are commonly applied to packages shipped by mail. The other two openings 3 and 4 are for the addresses of the sender and sendee, whose 65 names and addresses are displayed through the respective windows and are placed on a card 6, which is removably mounted at the inner side of the cover top.

The cover at its inner side below the openings 2, 3 and 4 therein, is provided with a backing board or member 7 of hard stiff material, such for instance as pressed fiber board and this is slightly spaced from the cover top by spacing strips 8, which co- 70 operate with the board 7 and cover top to form a guide-way 9 for the ribbon 5 and a pocket 10 for the card 6. The guide-way 9 is open at both ends to permit the passage of the ribbon 5 therethrough, preferably length- 75 wise of the opening 2, and the pocket 10 is open at one end to permit a removal and replacement of the card 6 therefrom and a replacement of the same. A catch member 11 is pivotally carried by the under side of 80 the cover adjacent to the open end of the pocket 10 and is turnable over the outer projecting end of the card 6 to releasably retain it in the pocket. If the container is not of sufficient length to permit a straight removal 85 of the card 6 from the pocket 10 the card may be of flexible material so as to permit a bending of the same up within an end portion of the cover when being removed from the pocket.

The display window 3 for the sender's 90 name is preferably located above and to the left of the window 4 so that the names of the sender and sendee will bear the customary relation to each other which is preferred by postal authorities, and which renders it 95 easy for a postal clerk to locate the name of the sendee in handling the packages.

A container of this character is intended more particularly for and is used to a very 105 large extent by persons sending packages back and forth to each other, as for instance, a college student sending laundry by parcel post to his home, the laundry then being returned to him in the same package, and for 110

such reason the card 6 is provided on opposite sides with the names of the sender and sendee in reversed positions so that if the package is being sent by Mrs. John Doe to 5 her son John Doe, jr., the side of the card will be used which displays her name in the sender's position and the latter's name in the sendee's position, and when the container is being used by John Doe, jr., to send laundry 10 or other matter to his home the card is reversed so that her name will be displayed at the sendee's window and John Doe's name at the window of the sender. The card may be easily and quickly reversed as is apparent 15 and the ribbon 5 is unwound from a supply roll 12 which is carried at one end of the guideway 9 by a forked bracket member 13.

It is evident that in the use of the container in being prepared for reshipment a 20 sufficient length of ribbon 5 is unwound and drawn through the guideway 9 to place a clean unstamped portion in register with the window 2, the surplus portion of the ribbon being torn from the strip at the opposite side of the guide-way 9 to the roll 12. The board 7 forms a firm backing for the ribbon 5 so that the latter may be written or stamped as desired. It is also evident that the container top is smooth on its outer side 25 except for the provision of the openings or windows 2, 3 and 4 therein, and that the ribbon 5 and card 6 as well as the parts guiding and carrying the same are disposed

at the inner side of the container so as not to interfere with the handling of the same. 35

I wish it understood that my invention is not limited to any specific construction, arrangement or form of the parts, as it is capable of numerous modifications and changes without departing from the spirit of the 40 claims.

Having thus described my invention, what I claim as new, and desire to secure by Letters Patent, is,—

1. A reshipment container having an 45 opening in a wall thereof, a ribbon roll mounted at the inner side of the container to permit the ribbon to be unwound therefrom and extended across the opening at its inner side, and guide and backing means for the 50 ribbon secured to the container wall at the inner side of the opening.

2. A reshipment container having an opening in a wall thereof, and a ribbon guide and backing means secured to the inner side 55 of the wall and extending across the opening, a ribbon roll carrying bracket secured to the inner side of the wall at one end of the guide means, and a ribbon roll carried by the bracket and adapted to unwind therefrom and extend through the guide means to receive postal stamps and markings on the part thereof exposed through the opening. 60

In testimony whereof, I have hereunto signed my name to this specification.

AMOS D. CRAWFIS.
